MACHINE FOR DYEING ARTICLES

Harry C. Wolfenden, Attleboro, Mass.

Application June 21, 1940, Serial No. 341,675

1 Claim. (Cl. 68—161)

My present invention is a novel and improved dyeing machine wherein yarns, cloth, and similar articles may be treated, colored, and dyed in an expeditious, efficient, and economical manner.

Heretofore it has been customary to dye yarn, cloth, and the like by applying the same to rotating frames with dye thru dye-colored liquid, and usually with the addition of steam or heat applied thereto. Thus, in a dye house, vast masses of steam emanate from the dyeing machines, causing considerable difficulty at times in the dye house for the operatives, and considerable damage to the structure of the dye house itself.

Efforts have been made to effect the dyeing operation in a closed receptacle which would, to a large extent, eliminate the difficulties heretofore experienced in the escaping of steam and moisture, and which would handle the more delicate dyes as well as finer yarns and articles.

It is also well known that the dyeing operation, if it can be performed in a partial vacuum and thus permit the liquid to be in a boiling state at a temperature less than 212° F. is beneficial to the articles being treated because of the lesser degree of heat to which such articles are subjected.

Also, it is important to keep the liquid containing the dye in agitation, and for this purpose steam or air has been utilized to effect a bubbling operation in the receptacle, and various combinations of steam for heating and outside air for creating the bubbling have been attempted.

None of these prior devices have been entirely satisfactory, and my present invention is to improve and perfect a closed dyeing receptacle, particularly adapted for treating finer yarns and the more delicate fibres in an efficient and economical manner to conserve the heat or steam employed, and to effect the dyeing operation in a receptacle to which there is a vacuum-creating tendency and also to produce an agitation by bubbling or forcing created air and vapor thru the bottom portion of the liquid by supplying said heated vapors from the upper portion of the receptacle itself, thus effecting a heat circulation in a closed manner without cooling the heated liquid, as was formerly the case where outside air was employed.

Thus, by means of my improved apparatus and by my present novel method of operating a dyeing machine of the closed type, I am enabled to conserve the heat required, and after the liquid and contents of the machine have been brought

up to the proper temperature, I can shut off the steam supply either automatically or by hand, and the dyeing operation performed for a considerable time without cooling the contents.

5 A further important feature of my present invention consists in the novel construction and arrangement of the yarn-holding stick and, furthermore, in the rotative action of such stick to prevent "stick marks" or undyed portions on the 10 yarn or article being treated.

If the yarn, when hung in a dyeing machine of any sort, is not lifted or removed from the sticks retaining the same, there will be an undyed portion or stick-mark which is a serious 15 defect. My invention eliminates the danger of such stick marks.

Furthermore, I have devised a novel, light, metallic stick member comprising a plurality of narrow rods of stainless steel or other non-corrosive metal, which will not be affected by the 20 dye and will not, in turn, affect the articles being dyed.

Furthermore, I provide means manually or 25 automatically operated, to effect a rotation, or partial rotation, of these carrying sticks so as to still further insure a complete and uniform dyeing operation and eliminate all possible danger of stick marks.

30 A still further feature consists in providing means which will eliminate the danger of skeins of yarns from becoming tangled, knotted, entwined, or the like during the agitating and bubbling action. By supplying heated vapor thru the bottom portion of the receptacle there is, of 35 course, a mass of bubbles rising thru the heated liquid which would normally tend to tangle skeins of yarn suspended therein, and I have provided simple and efficient means for preventing the same, as will be herein more fully explained.

In carrying out my invention I provide a suitable tank or receptacle to receive a framework, which may be raised over and lowered into the 45 receptacle, as desired.

This framework is of non-corrosive metal and the tank or receptacle is also of non-corrosive material, or is lined with the same. I find that stainless steel is suitable for this work, as it 50 neither is injured by the dye nor injures the dyed material in contact therewith. Such framework is adapted to carry a considerable number of sticks, each stick carrying a plurality of skeins, and said framework is preferably adjustable for different lengths of skeins or material being

dyed and thus permit a lower level of liquid in the receptacle where shorter skeins are used.

The yarn-carrying sticks are of novel construction and, preferably, include a pair of discs united by three or more thin, non-corrosive metal rods, and I provide means to automatically rotate or oscillate these sticks in unison irrespective of the length of the skein or other material.

I also provide similar rotated sticks to hold the bottom portions of each skein against displacement to eliminate tangling during the bubbling operation. Suitable heating means, such as steam pipes, are supplied in the bottom of the receptacle and an air-tight covering for the top is also applied. Near the top I provide an outlet with an exhaust fan, blower, or other means to draw from the top of the interior of the closed receptacle the vapors, steam, and heated air and conduct same thru a series of perforated pipes in the bottom of the receptacle adjacent the heating pipes.

Thus, when the receptacle is filled with liquid and dye, and a loaded frame lowered therein, immersing the yarn in the dyeing liquid, securing the cover, and supplying the steam for heating, the agitating means consists in withdrawing from the top of the receptacle, above the level of the liquid, the heated vapors and forcing same into and thru the bottom portion where they produce a bubbling and agitating action as these heated vapors rise thru the liquid dye.

By thus preheating the bubble-creating and liquid-agitating vapors, I am enabled to conserve heat, and, with the liquid-tight cover and receptacle, the contents of the receptacle when once heated to the desired degree will maintain this heat for a substantial and considerable length of time, even though the steam is shut off. Thus, I can supply steam to the receptacle and then shut it off while in operation and it will continue to operate at an efficient temperature.

Furthermore, by the operation of withdrawing the vapors from above the liquid level in my type of closed receptacle, there is a decided tendency to create a vacuum within the receptacle and, thus, to maintain the efficiency of the heated liquid without a substantial lowering of the temperature because of this vacuum-creating means. Suitable liquid and dye-filling attachments are provided and mechanism for effecting a predetermined rotation or oscillation of the yarn-carrying sticks is also provided.

Both rotating means and the fan blower, or circulating device, are readily controlled either by hand or automatically by controls for a motor which may be attached to the cover, and the frame also may be attached to the covers so that the raising or lowering of the same is readily accomplished.

Other features, advantages, and novel combinations and the improved method of my present invention will be hereinafter more fully pointed out and claimed.

Referring to the drawings illustrating a preferred embodiment of the machine carrying out my present dyeing machine,

Fig. 1 is a side elevational view partly in cross-section;

Fig. 2 is a plan view showing the bottom of the receptacle with the framework removed and illustrating the steam-heating, bubble producing and dye-supply pipes;

Fig. 3 is a side elevational view looking from the right of Fig. 2;

Fig. 4 is a side elevational view of the right

side of the tank or receptacle looking from the front of Fig. 2;

Fig. 5 is an end view of the yarn-carrying frame and attached cover;

Fig. 6 is a view partly in cross-section showing the side of the yarn-carrying frame and a portion of the attached cover;

Fig. 7 is an enlarged perspective view of my novel type of yarn-carrying stick;

Fig. 8 is a cross-sectional view on an enlarged scale of the receptacle when closed and the framework in position with the yarn or material omitted, for clarity;

Fig. 9 is an enlarged fragmentary and cross-sectional view illustrating the attachments and operating means for rotating the yarn-carrying sticks, and

Fig. 10 is a fragmentary view illustrating the spring-holding means retaining the bottom series of yarn-holding sticks in position when attached to the frame.

Fig. 11 is a fragmentary view illustrating a modification wherein a large number of article-carrying sticks are fitted to the frame by staggering the same.

As shown in the drawings, for illustrative purposes, a suitable tank is provided having a base 1 and sides 2-2, with an open top to which a cover 3 is adapted to be fitted in liquid-tight and air-tight relation by resting on rubber gaskets 5 fitted in grooves 6 in the top edge portions of the sides 2. A plurality of lugs 7-7 are attached to the cover 3 with notches thru which the shanks of clamping screw 8-8 pass, each screw being pivoted at 9 to a bracket 10 secured to the sides in alignment with the lugs 7, a rotatable thumb nut 12 being threaded on the shank 8 of each screw and bearing on the lugs so as to clamp the cover in tightly assembled position, and forming a tight enclosure on the receptacle.

While I have herein shown the receptacle as built up of wood, or other suitable material, and lined with metal, the same of course may be made entirely of metal. In the particular form shown in the drawings, a metal lining 15 of rustproof material lines the side and bottom of the interior of the tank. The interior of the tank or receptacle is supplied with a series of heating pipes 20 from an inlet 21 thru an end 2, and an outlet 22 being connected with any suitable source of steam supply, shut-off valves as indicated at 23 being also provided to turn the heat on or off, as desired, and to permit the apparatus to operate without steam supply to conserve the steam and reduce expense, as above mentioned.

These steam pipes 20 are preferably arranged in the extreme bottom portion of the tank, as shown, and in any suitable radiating capacity for the tank, quantity of liquid, and work desired. I also provide a series or set of dye-carrying pipes, as indicated at 25-25, here shown as being a pair of pipes arranged at opposite side portions of the bottom of the receptacle, which pipes are to receive supplies of dyeing material, as desired, these pipes leading thru outlets 26 near the base of the receptacle and connected with conduits 27-27 to a Y-fixture 28, permitting both supply pipes 26 to receive dyeing liquid from a hopper 30 thru a connecting pipe 29 as best shown in Figs. 3 and 4. A valve 31 controls the supply of same.

Each of these dye-supply pipes 25 are provided with a series of holes or openings 33, preferably in the underneath portion of the pipes 25 so

that the dye, when poured into the hopper 30 and with the valve 31 open, flows into each pipe 25 and is distributed thruout the area of the bottom portion of the interior of the receptacle. In order to fill the tank with water, a supply pipe 35 is shown entering the tank near its lower portion, as at 36, and connected to any suitable source of supply. As illustrated, either hot or cold water can be supplied thru a pipe 35 by branch connections 37 and 38, see Fig. 3. An outlet and stopper 39 near one corner of the tank serves to drain the same for cleaning and changing the dye liquid.

In order to provide a circulation of the heated vapors and air accumulating in the closed tank during the dyeing operation by my present process, I arrange an outlet near the top of the tank above the extreme level of the liquid for any dyeing operation to be formed therein. Such outlet is shown at 40, from which an exhaust pipe 41 leads to an exhaust fan, pump, or the like 42, and thence downwardly thru a conduit 43 and connecting pipe 44 to the inlet 45 thru substantially the center of the bottom portion of the tank.

For this purpose I provide the base 1 with a horizontal channel 46 and a central manhole 47 to give access to the assembling of the conduit and inlet thru an elbow 48, see Figs. 1 and 8. The inlet 45 entering the bottom of the tank substantially in the center of the same is connected with a central distributing pipe 50 from which radiate a series of conduits 51, 52, 53, and 54, see Fig. 2. Preferably, the opposite side conduits 53 and 54 extending widthwise and lengthwise of the tank area each connected at their outer ends with conduits 55 and 56 extending lengthwise of the tank and in parallelism with the connecting pipes 51 and 54, see Figs. 2 and 8. Any other suitable arrangement can be made, if desired, but I wish to supply a plurality of air and vapor-conducting pipes with outlets there-thru spread over the bottom of the tank to effect the bubbling operation up thru the liquid.

Each of these pipes 51, 52, 53, 54, 55 and 56 are provided with a series of small holes or openings, as indicated at 60 in Fig. 1.

In operation, with the cover closed and the dyeing liquid at a suitable level to immerse the articles to be dyed, as indicated at 61, Fig. 1, the operation of the fan 42 draws the heated air and vapors from the interior of the tank above the level 61 and forces the same into the bottom portion of the liquid thru the delivery device containing the openings 60, thus producing a constant agitation throughout the entire mass of the liquid dye bubbling up therethru from the bottom to the top surface, thus maintaining the dye in agitation as well as the yarn suspended in the tank and being heated, and, in effect, a closed circuit pumping around from the top of the tank to the bottom. No cooling effect from this bubbling operation is produced and, hence, the steam supply having once brought the interior of the tank to the proper temperature can be shut off for considerable period of time.

Furthermore, the operation of the fan 42 tends to create a slight vacuum in the interior of the tank, thus facilitating the dyeing action at lower temperatures than 212° and, hence, helps eliminate the danger of damage to delicate yarns being treated.

While the bubbling action effected by the series of openings 60 in the delivery pipes is substantially uniform, I may, if desired, apply a perfo-

rated plate 63, having a large number of holes 64 therethru, positioned directly over all the steam, dye-supply, and air-supply pipes, which plate may rest on a series of blocks 65—65 and constitutes a protecting and distributing member.

I consider that this feature of a closed and heated circulating system in dyeing apparatus of this kind is most important, increasing the efficiency of the dyeing operation, cutting down the time, increasing the penetrating effect of the dyeing material, conserving heat, saving steam, and also obtaining the benefit of the dyeing operation in a partial vacuum.

Any suitable means may be supplied for placing the articles to be dyed in my improved treating tank. Preferably, and as herein shown, I provide a metal framework also of non-corrosive metal like the lining 15, which framework has a capacity for vertical adjustment so that shorter lengths can be dyed in shallow depths of water than the extreme high level shown at 61 and, thus, conserve heat and dye when shorter articles are being treated. Also, I provide such a framework, preferably, with my improved type of rotating yarn-carrying stick, and I rotate the same automatically and at any height to which the frame is adjusted, as will be explained. While such a framework may be handled, lowered into, positioned in, and raised from the tank in any convenient manner, I prefer to attach the same to a cover 3.

For this purpose I secure to the underneath part of the cover 3 suitable frame members 75, to which are secured four depending angle irons 76 with suitable clearance between the outside of the same and the lining 15 of the interior of the tank, so that the entire frame and cover may be readily lowered into and lifted above the top of the tank for filling the frame with the articles to be dyed, and removing said articles therefrom after the dyeing operation.

The top portions of these vertical side frames 76 are rigidly secured to the cover 3 and cross-frames 75 and the bottom portions are held by braces 77. Adjustably secured lengthwise of the tank and to the vertically extending frames 76 are a pair of lengthwise horizontal frames 80. Any suitable adjustment can be provided to unite these frames 80 with the vertical frames 76, but, as herein illustrated, I have provided a slot 81 in each of the vertical frames and a pair of bolts 82 thru the end portions of each horizontal frame 80, which bolts engage the slots 81, and thus the lengthwise frames 80 may be raised or lowered within the limits afforded by the length of the slots 81 and, thereupon, the bolts 82 tightened and each top frame 80 is held in adjusted position. A corresponding lower lengthwise frame 84 is also provided and this can be rigidly secured to the lower portions of the vertically extending frames 76 as by bolts 85.

The top lengthwise frames 80 are fitted to receive and hold the yarn-carrying sticks, which sticks are rotated and, similarly, the lower lengthwise frames 84 are adapted to receive and carry yarn-engaging sticks so as to hold the yarn masses and prevent tangling, knotting, and damage during the dyeing action, and particularly because of the effect of the bubbling operation upwardly thru the liquid in the tank.

While this framework can be utilized to carry any standard type of yarn-carrying stick, I prefer to utilize my novel type of rod construction as best shown in Fig. 7. My improved stick con-

struction comprises a pair of discs 88 and 89 connected by a series of rods 90 spaced substantially at equal distances around the periphery of each disc 88 and 89 and secured thereto and by fitting thru holes or recesses in the discs and being welded therein. These rods and discs are also of non-corrosive metal. The disc 89 is fitted with a square or other angular projection 91 to fit within the interior of the gear wheel so that the gear may turn said stick; while the opposite disc 88 is provided with a hub or axle 92 to fit within the bearing. Each hub 92 is provided with a groove 93 to receive a locking pin 94—94 carried by one of the frames 80 in which these hub ends are to be fitted, the opposite frame 80 having recesses thru which the squared end 91 of the driving portion may be fitted.

As shown in Fig. 10, the frame 80 in which the hub or axle members 92 of each stick are attached has a series of U-shaped openings 95, so that these axles may rest therein and then be locked in the lower part of the U by the rods 94, which latter are actuated by springs 97 mounted between upstanding flanges 98—98 on a plate 100 secured to the frame 80 adjacent each U-shaped opening 95, in position to permit the rod 94 to be moved across the U-shaped opening engaging each groove 93, and thus locking this end of the stick in position.

A finger pin 101 is attached to each rod 94 to move the same backward against the spring 97 and this releases the hub 92 and permits withdrawal of this end of the stick. As a further locking means on the opposite side of the finger and spring, a flanged plate 102 is fitted with a recess into which the end of the sliding rod or bolt 94 fits to hold this end of the rotatable rod or stick in locked position.

If desired, I may add one or more braces, as shown at 99, Fig. 7, between the discs 88 and 89 to keep the rods 90 in proper spaced relation. It will be appreciated that my type of rotatable stick with a plurality of rods eliminates to a large degree the possibility of marking the yarn, or other material, hung thereon; but in order to still further eliminate the danger of such marking, as well also as to insure an even and uniform dyeing operation, I prefer to provide means which will rotate or oscillate the rods during the dyeing operation.

Also, it may be desirable, and I have herein illustrated means to correspondingly rotate or oscillate the lower sticks in synchronism with the upper sticks. For this purpose, I provide a shaft 105 extending upwardly thru the top of the cover 1 to the gear box 106 operated by a motor 110 positioned adjacent thereto and secured on top of the cover, said shaft 105 extending downwardly thru bearings in brackets 112 and 113 bolted to the side of the end frame 76, see Fig. 5, which shaft has a sliding and telescoping connection, as indicated at 115, to permit the raising and lowering of the topmost lengthwise frame 80, the lower end of the shaft being also fitted to rotate thru bearings 117 and 118 in alignment therewith near the lower portion of the frame.

A worm 120 is splined on the shaft 105 to turn therewith and slide thereon during the raising and lowering of the top lengthwise frame 80; and a similar worm 121 is keyed on the lower end of the shaft in alignment with the lower frame 84. Each of these worms mesh with a gear 122 mounted on studs 123, see Fig. 6, and each has a pinion 124 meshing with adjacent gears 125—125

fitted on studs lengthwise of the cross-bars 80 and 84, said pinions and gears having a hollow central recess 126, see Fig. 9, into which the squared or angular end 91 of a stick fitted in the frame in alignment therewith will register. I may make these hollow centers of each pinion in the form of a separate hub 129 secured by a headed bolt 130 for assembling purposes, see Fig. 9.

With a set of these sticks provided with a series of skeins of yarn 133, see Fig. 5, they are then fitted on the frame, first forcing the end block 91 on each end 89 into the recess 126 of an adjacent gear, and then with the opposite end lowered into a notch 95 and locked in position with a sliding bolt or rod 94 in the opposite frame. Thereafter, a lower stick is threaded thru the skein yarns and, similarly, fitted in position in the lowermost frames 84, and thus the frame is loaded while the cover 3 is raised and the frame is above the tank. Thereupon, the frame is lowered into position in the tank, the cover resting on the gaskets 5, the clamps swung into position and thumb nut 12 rotated to tighten the cover in air-tight relation to the tank.

In order to conveniently operate the cover and frame any suitable or desirable mechanism can be employed. As herein shown, I utilize a ball comprising a lifter 140 with four branch arms 141—141 extending to the four corners of the cover 3 secured to eye-bolts 142, set in cross-bars 143 attached to the cover, or otherwise secured, and adapted to be raised or lowered by a pulley and any suitable source of power.

If it is desired to rotate the shaft 105, the motor 110 may be actuated therefor thru the gear box 106, which would also include a suitable reduction gear, but if it is desired to oscillate the shaft 105, I then provide a control box 144 which will automatically shift the rotation of the motor from one direction to the reverse, thus oscillating the shaft 105 and turning the sticks a predetermined number of times in one direction, and then in reverse direction during the time required for the treating action.

With the frame loaded with articles to be treated, such for example as skein yarns, and with the top frames 80 adjusted for the length of the yarn or other articles being thus dyed, the frame is first lowered into the tank, the cover clamped, liquid and dye either having been supplied beforehand, or then being supplied, together with additional liquid dye added from time to time as desired, and the steam turned on to heat the same, the motor is actuated to oscillate or rotate the yarn-carrying sticks; and when a proper temperature has been reached or at any other time deemed suitable, the exhaust fan 42 is actuated, preferably by electrical means (not shown) and the vapor accumulating above the level 61 in the tank is drawn from the top and forced in, to, and thru the bottom portion of the liquid in the distributing pipes 51 to 58, flowing out of the holes 60 and upwardly thru the mass of liquid and thru the yarn being treated, thus keeping the entire contents in agitation.

Because the tank is thus closed, the heat is retained, and because I employ a closed circulating system, forcing preheated vapor into and thru the tank, the steam heating supply can be shut off for upwards of one-third the time required for the treating action.

A suitable window 145, to permit inspection of the contents, is shown in the cover 3 but a simi-

lar window, or windows, can be, if desired, placed in the sides at any point, or points, which seem practicable. Also, I provide a pair of protecting rods 150 extending adjacent each end portion of each set of sticks, both those on the top frames 80 and the lower ones 84, as guards to keep the yarn skeins from working near the end of each stick. These rods are conveniently secured thru the angle-iron frames by bolts as shown at 157, Figs. 1 and 5.

In Fig. 11 I have illustrated a modified construction wherein the lengthwise horizontal frames 80 are provided with a plurality of sets of driving gears on one frame and slots on the opposite to permit the yarn-holding sticks to be positioned in staggered relation, thus enabling a frame to carry a larger quantity of material being dyed. Thus, the apparatus can be utilized to be filled with a series or set of sticks in either the lowermost stick-carrying and rotating device, or topmost, or both, and in the latter case practically doubling the carrying capacity of the frame. Furthermore, this arrangement of an upper and lower set of sticks provides for a slight adjustment in the length of yarn or skeins being treated without manually adjusting the horizontal frames 80 to take care of same.

Thus my improved apparatus can be quickly adjusted for any size or length of skein or material to be treated, is efficiently operated, conserving heat, saving time, penetrating the fibres more thoroughly, insuring a more "lofty" product, and acting in keeping the distortion of the fibres to a minimum more nearly like the original product and largely eliminating the matting or

snarling so prevalent with skein dyeing, modifying considerably the danger of stick marks and obtaining the advantages of the dyeing operation in a partial vacuum, and the fact that the machine is totally enclosed the greater part of the time, eliminating the steam getting into the building which is most detrimental to the construction of same causing excessive rotting and deterioration, which has always been a serious factor in dyehouse construction.

I claim:

Apparatus of the kind described for dyeing yarn and the like, comprising a liquid-tight receptacle and a removable cover adapted to be raised and lowered in alignment with said receptacle and to constitute a pressure-tight cover when in lowered position, means for locking said cover in air-tight relationship to the receptacle, a yarn-carrying framework attached to said cover, said frame comprising two pairs of vertically extending members and two pairs of horizontally extending cross-members, the upper cross-member being secured to said vertical member with provision for vertical adjustment thereon, both cross-members carrying rotatable yarn-carrying sticks, said sticks being removably attached to said cross-members, interlocking gears on one end of the sticks carried by one set of the cross-members, and means to rotate said gears from a suitable source of power carried on the outside of said upper cover in any spaced relation to which said cross-member may be adjusted on the vertical members.

HARRY C. WOLFENDEN.
